Primary Examiner — Janice Patyk*Assistant Examiner* — Ji Sun Yoon(74) *Attorney, Agent, or Firm* — Dinsmore & Shohl LLP**CLAIM**

The ornamental design for a combined cooler and latch as shown and described.

DESCRIPTION

FIG. 1 is a top perspective view of a combined cooler and latch, showing our new design;

FIG. 2 is a bottom perspective view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof; and,

FIG. 8 is a bottom plan view thereof.

The broken lines in the figures illustrate portions of the combined cooler and latch and form no part of the claimed design.
